UNITED STATES PATENT OFFICE.

GEORGE C. HOEFLER, OF NEW HAVEN, CONNECTICUT, ASSIGNOR TO THE ANDREW B. HENDRYX CO., OF NEW HAVEN, CONNECTICUT, A CORPORATION.

DESIGN FOR A BIRD-CAGE.

43,280.

Specification for Design.

Patented Nov. 26, 1912.

Application filed August 29, 1912. Serial No. 717,794. Term of patent 14 years.

To all whom it may concern:

Be it known that I, GEORGE C. HOEFLER, a citizen of the United States, residing at New Haven, in the county of New Haven and State of Connecticut, have invented a new, original, and ornamental Design for a Bird-Cage; and I do hereby declare the accompanying drawing to be a full, clear, and exact illustration of the same, and which said drawing constitutes part of this appli-

cation, and represents a perspective view of a bird-cage embodying my design.

I claim:

The ornamental design for a bird cage, as shown.

GEORGE C. HOEFLER.
